UNITED STATES PATENT OFFICE.

JOHN F. CONNELLY, OF SPRINGFIELD, ILLINOIS.

OIL DISPENSER.

1,403,670.

Specification of Letters Patent. Patented Jan. 17, 1922.

Application filed October 28, 1920. Serial No. 420,088.

To all whom it may concern:

Be it known that I, JOHN F. CONNELLY, a citizen of the United States, residing at Springfield, in the county of Sangamon and 5 State of Illinois, have invented a new and useful Oil Dispenser, of which the following is a specification.

The invention relates to improvements in 10 appliances for displaying and dispensing oil or other liquids.

The purposes of the invention are:—to provide a dispenser comprising a transparent vessel for containing a measured quantity of liquid, which will be visible in order that 15 the buyer may see that he is getting the quantity of liquid to which he is entitled; a metal casing detachably connected with the container and protecting it against accidental breakage; a funnel for conveying the liquid 20 while being discharged; means admitting of filling the container while the funnel is attached thereto; means for admitting air to the container to facilitate the flow of the liquid therefrom; and an extension, detach- 25 ably connected with the funnel and adapted to permit the discharge of the liquid into tanks or vessels inaccessible to the funnel proper.

The invention is primarily designed for 30 the display and dispensing of oil, but is obviously equally effective for displaying and dispensing other liquids.

The invention is illustrated in the annexed drawing to which reference is hereby made, 35 and will now be described and the novel features thereof will be recited in the claims.

Figure 1 is a side elevation of an oil dispenser, embodying my invention; Fig. 2 is a plan view of the blank from which the casing is formed; Fig. 3 is an enlarged longitudinal sectional view showing the internal construction of the air duct and valve; and Fig. 4 shows a fragment of the funnel and a screw cap thereon. The same reference numbers designate the same parts in all the views.

The container 1 is preferably a glass Mason fruit jar of the capacity of a pint, a quart, or a half gallon; as the case may be, as said 50 jars have standardized screws so that a cap or funnel fitted to the screw of one jar will fit on any other jar.

The elongated funnel 2 is of sheet metal and the expanded part 3 of the funnel has 55 screw threads 4 engaging on the screw of the container. The funnel also has an intake

member 5 provided with a screw cap 6. At the reduced terminal of the funnel are screw threads 7. A strainer 8, preferably of wire gauze, is fixed in an oblique position in the 60 funnel.

One of the main uses of the appliance is to dispense oil to automobiles, the oil containing chambers of which are variously located. In some cases the containers are inaccessible 65 by means of a straight funnel. I therefore provide an extension 25 of sheet metal screwing onto the screw 7. When it is necessary to use the extension it will be attached as shown in Fig. 1, in other cases the extension 70 will not be used.

The air duct, and the valve contained therein, shown in Fig. 3, will now be described. The tubular air duct comprises an outwardly extended member 9 and a member 10, extending upwardly almost the entire length of the funnel and in communication with the member 9. At the inner terminal of the air duct is a cylindrical valve-body 12 brazed on the air duct and having outlet 80 openings 13. The valve-body 12 has internal screw threads 14. The valve stem 15 has an enlarged conical member 16, adapted to seat on a flared valve seat 17 at the inner end of air duct, and an integral screw 18, engaging the screw threads 14. A pin 19, extends through the stem 15, and serves as a handle to rotate the stem. In assembling the valve mechanism the stem 15 will be inserted through the valve-body 12 and through the 85 duct 9. The pin 19 will then be placed in position transverse to the stem, and using the pin as a handle, the screw 18 will be rotated to cause the member 12 to engage firmly on the seat 17, so that air will be excluded 90 from the interior of the casing 12. The operation of the air duct and valve will be described later.

The protective casing, designated as a whole by the numeral 20, is pressed from a 100 single sheet of metal and comprises a polygonal body with radiating staves 21. The staves are bent upwardly along the lines 23. Each stave has tongues 22, pressed from the metal of the stave, and adapted to support 105 wires 24, which bind the staves together. The staves extend upwardly beyond the flared terminal of the funnel; and the wire connecting the upper terminal parts of the staves prevents detaching of the funnel 110 without removing the wire. It is rarely necessary to remove the funnel except in

case of breakage of the container. The casing protects the container so that with ordinary care there is little danger of breaking the container.

5 The mode of using the appliance is as follows:—The funnel will be screwed on to the container and the container will be placed in the casing and the wires 24 will be placed on the hooks 22, and the ends 10 twisted together to securely connect the container, the casing and the funnel. Preliminary to filling the container the valve 16 will be tightly closed so that oil cannot enter the air duct. The cap 6 will be unscrewed and oil will be introduced through the intake 5. If it is desired to use the straight funnel the tapered terminal of the funnel will be inserted in the opening in the oil reservoir, and the valve 16 will be 15 opened to permit air from the air duct to pass through the opening 13 of the valve-body into the space above the oil in the inverted container, thus admitting air to facilitate the flow of liquid through the 20 funnel, and if the flow is too rapid the valve will be closed more or less to retard the flow of liquid as may be desired. If the opening in the oil reservoir is not accessible to the straight funnel the angular extension 25 will be attached and its free end will be inserted 25 in the opening in the reservoir.

Having fully described my invention, what I claim as new, and desire to secure by Letters Patent is:—

35 1. In an appliance of the class described, the combination of a transparent container having a screw-threaded portion, a funnel having an expanded screw threaded member engaging the screw-threaded portion of the 40 container, a protected intake opening; an air

duct, extended outwardly through the funnel and extended upwardly inside the funnel, and a valve controlling the admission of air through said air duct.

2. In an appliance of the class described, 45 the combination of a funnel; an air duct having a member extended outwardly through the wall of the funnel and a member extended upwardly inside the funnel; a valve stem extending downwardly through 50 the outwardly extended member of the air duct; a valve body fixed on the air duct; a valve seating on the inner terminal of the air duct; and a screw operative upon rotation of the valve stem to open or close the 55 valve.

3. In an appliance of the class described, the combination of a one piece protective casing comprising staves spaced apart from each other and provided with hooks; a container inside the protective casing and having a screw; a funnel engaging on the screw of the container; and wires connecting the staves, the container and the funnel. 60

4. In an appliance of the class described, 65 the combination of a container; a funnel connected with the container; and a branched and valved air duct extending downwardly into the container and upwardly into the funnel and adapted to permit the intake of air through the air duct and prevent the escape of oil through the 70 air duct.

In witness whereof I have hereunto signed my name at Springfield, Illinois, this 25th 75 day of September, 1920.

JOHN F. CONNELLY.
